INVENTOR

Otto H. Dorsch

BY Carl P. Geiger
ATTORNEY

UNITED STATES PATENT OFFICE.

OTTO H. DORSCH, OF BROOKLYN, NEW YORK.

BRUSH.

1,216,666.

Specification of Letters Patent. Patented Feb. 20, 1917.

Application filed April 29, 1916. Serial No. 94,327.

To all whom it may concern:

Be it known that I, OTTO H. DORSCH, a citizen of the United States, and resident of Brooklyn, in the county of Kings, State 5 of New York, have invented certain new and useful Improvements in Brushes, of which the following is a specification.

The present invention relates to improvements in brushes, and particularly a 10 rubber brush for use in the cleaning of bottles, an object of the invention being to provide such a brush which may be operated in a most effective manner, and capable of directing the supply of water so that it will 15 have the greatest cleaning effect. It is also an object to provide such a brush which will clean all portions of the interior of the bottle, and will be comparatively long lived, thereby materially reducing the cost of 20 operation in plants employing such brushes.

With these and other objects in view, my invention is shown in the accompanying drawings and will be hereinafter more fully described with reference thereto, and finally 25 pointed out in the claims.

In the accompanying drawings:

Figure 1 is a front view of my improved brush,

Fig. 2 is an edge view of the same,

Fig. 3 is a top view thereof,

Fig. 4 shows the brush drawn into the guide tube before insertion into the bottle,

Fig. 5 shows the same being inserted 35 into the bottle and engaging the neck portion thereof, and

Fig. 6 shows the brush within the bottle.

Similar reference characters indicate corresponding parts throughout the several figures of the drawings.

Referring to the drawings, and more particularly to Fig. 1 thereof, my improved rubber brush comprises a stem 10 having a passage 11 therethrough, and enlarged slightly at its lower end 12, where it is 40 attached to a screw threaded ferrule 13, provided on the end of a revolving spindle 14. It is unnecessary to interiorly thread the portion 12 of the brush, as the rubber will conform by reason of its tight engagement to the threads of the ferrule. At the 45 upper end of the stem there are provided a pair of outwardly extending arms 15 and 16. A reinforcing rib 17 extends along each side of the stem, and is continued along the 50 arms, terminating in pairs of leaves 18 and 19 respectively on each of the arms. The 55 said leaves are in the form of halves of spear points. Grooves 20, 21 are provided along the inner face of the arms, continuous with the passage 11. 60

At each side of the stem there are provided a plurality of fingers 22, preferably three on one side and two on the other in alternating relation. Reinforcing ribs 23 are provided on the rear faces of the fingers 65 at right angles thereto, and of gradually increasing depth from the outer end of the surface of the stem, the same being integral at this point with the stem.

In operation, a plurality of guide tubes 70 24 are provided, into which the brush may be drawn, and the bottles 25 to be cleaned are moved in inverted position over the tubes. Fig. 4 shows the position of the brush when drawn into the tube preliminary 75 to the cleaning operation. It will be noted, that when the brush is drawn within the tube, the arms 15, 16 are brought into contacting relation, exactly in the center of the tube, and an unobstructed passage for admission of water is formed by the grooves 80 20, 21 continuous with the passage 11. Water is forced through this passage under a pressure of approximately fifteen pounds, and the brush is revolved counter-clockwise 85 at approximately 1500 revolutions per minute. As the brush is moved upwardly in the bottle, the water is continuously injected therein, and a thorough and forceful cleaning begins at the mouth of the bottle 90 and continues to the bottom thereof. The brush forcefully engages every portion of the neck, and as the bottle gradually widens, the fingers move outwardly into engagement with the sides of the bottle. The brush 95 being about one quarter of an inch wider than the interior of the bottle, the ends of the fingers engage the sides with considerable force, the ribs 23 holding the fingers rigid. The centrifugal force caused by revolving the brush, forces the arms 15, 16 outwardly, and the grooves 20, 21 direct the water to the sides of the bottle. When the brush reaches the bottom of the bottle 100 the arms are spread out horizontally, or if the interior of the bottle is curved, into a conforming shape. Practically four sharp edges formed by the grooves engage the bottom, and a thorough cleaning takes 105 place, the water being at all times effectively directed by the grooves, which prevent stopping of the water supply passage. 110

The leaves 18, 19 engage the curves of the bottle, and effect a thorough cleaning at these points. After one cleaning operation the brush is retracted into the guide tube, 5 and the cleaned bottles removed, whereupon another set are brought into place and the operation repeated.

I have illustrated a preferred and satisfactory form of my invention, but it is obvious that changes may be made therein 10 within the spirit and scope thereof, as defined in the appended claims.

I claim:

1. An improved bottle brush comprising 15 an elongated flexible stem portion provided with a longitudinal passage therethrough, a plurality of arms at the end of said stem normally inclined outwardly from said stem, provided on the inner surfaces thereof with 20 grooves formed continuous with the said passage of the stem, said arms adapted to be pressed into contacting relation, said grooves adapted to maintain an uninterrupted passage continuous with said passage 25 of the stem, and a plurality of relatively long fingers extending outwardly from the sides of said stem.

2. An improved bottle brush comprising 30 an elongated flexible stem portion provided with a longitudinal passage therethrough, a plurality of arms at the end of said stem normally inclined outwardly from said stem, provided on the inner surfaces thereof with 35 grooves formed continuous with the said passage of the stem, said arms adapted to be pressed into contacting relation, said grooves adapted to maintain an uninterrupted passage continuous with said passage 40 of the stem, and a plurality of equal length relatively long fingers extending outwardly from the sides of said stem, said fingers being supported at the rear faces by reinforcing ribs, and unsupported at the front faces.

45 3. An improved bottle brush, comprising an elongated flexible stem portion provided

with a longitudinal passage therethrough, a plurality of arms at the end of said stem normally inclined outwardly from said stem, provided on the inner surfaces thereof with 50 grooves formed continuous with the said passage of the stem, said arms adapted to be pressed into contacting relation, said grooves adapted to maintain an uninterrupted passage, continuous with said passage of the 55 stem, outwardly extending leaves at the upper end of said arms, and a plurality of relatively long fingers extending outwardly from the sides of said stem.

4. An improved bottle brush, comprising 60 an elongated flexible stem portion provided with a longitudinal passage therethrough, a plurality of arms at the end of said stem normally inclined outwardly from said stem, provided on the inner surfaces thereof with 65 grooves formed continuous with the said passage of the stem, said arms adapted to be pressed into contacting relation, said grooves adapted to maintain an uninterrupted passage, continuous with said passage of the 70 stem, and a plurality of equal length relatively long fingers extending outwardly from opposite sides of said stem, the fingers at each side being in the same vertical plane.

5. An improved bottle brush, comprising 75 an elongated flexible stem portion provided with a longitudinal passage therethrough, a plurality of flexible arms at the end of said stem adapted to be moved outwardly by centrifugal force, and a plurality of 80 equal length relatively long fingers extending outwardly from said stem, said fingers being in the same vertical plane as said arms.

In testimony that I claim the foregoing 85 as my invention, I have signed my name in presence of two subscribing witnesses.

OTTO H. DORSCH.
